UNITED STATES PATENT OFFICE.

FREDERICK JACOB, JR., OF NEWARK, NEW JERSEY.

ATTACHMENT-HOLDER FOR SEWING-MACHINES.

SPECIFICATION forming part of Letters Patent No. 705,354, dated July 22, 1902.

Application filed April 18, 1902. Serial No. 103,506. (No model.)

To all whom it may concern:

Be it known that I, FREDERICK JACOB, Jr., a citizen of the United States of America, residing at Newark, in the county of Essex and State of New Jersey, have invented certain new and useful Improvements in Clamping Devices, of which the following is a specification.

My invention has reference to improvements in clamping devices, and particularly to devices adapted for holding attachments rigidly and firmly to the presser-bars of sewing-machines, my said invention having for its objects the provision of a socket readily attachable to the presser-bar of a sewing-machine or other bar and to provide the several attachments with shanks adapted to be received by the socket all in the same manner or direction and to be subsequently retained within the socket by simply turning the fastening-screw.

With these objects in view my invention consists, essentially, in a socket provided with a diametrical slot, a screw arranged transversely to the slot and provided with a tapered inner end adapted to cross said slot, and an attachment-piece formed to enter said slot in the socket and provided with a tapered recess adapted to be engaged by the screw, all for the purpose of drawing the attachment upwardly within the slot.

My invention also consists in further novel features of construction, all of which will best be understood when described in connection with the accompanying drawings, in which—

Figure 1 represents a side view of a presser-bar provided with my improved socket and a presser-foot secured within said socket. Fig. 2 is a vertical section thereof. Fig. 3 is a horizontal section on the line 3 3, Fig. 1. Fig. 4 is a rear view of the presser-foot. Fig. 5 is a perspective view of a modified form for the attachment end of the presser-foot. Fig. 6 is a horizontal section on the line 6 6, Fig. 5. Fig. 7 is a vertical section showing the socket and attached presser-foot. Fig. 8 is a rear view of another modified form for the attachment end of the presser-foot. Fig. 9 is a horizontal section on the line 9 9, Fig. 8. Fig. 10 is a side elevation showing the socket and attached presser-foot.

Similar letters and numerals of reference designate corresponding parts throughout the several views of the drawings.

Referring now to the drawings, the letter A designates the presser-bar of a sewing-machine. B is the socket attached thereto, and C is the presser-foot. The socket B is bored out longitudinally for the reception of the presser-bar A, to which said socket is secured by means of a set-screw 2. Into the socket B is also cut a diametrical slot 3, extending in the direction of the length of said socket upwardly from its lower end. The socket is transversely drilled and threaded for the reception of a screw 4, having a tapered end 5, and is also preferably provided in line with said screw with an opening 6, although this opening is not absolutely essential.

The attachment end 7 of the presser-foot C is in the present instance in the form of a rectangular shank adapted to enter the diametrical slot 3 of the socket B from one side and is provided with a transverse tapered depression or opening 8, which is adapted to be engaged by the screw 4 when the shank is inserted into the diametrical slot. The tapered depression or opening 8 is located substantially the same distance from the upper end of the shank 7 as the axis of the screw 4 is from the top of the diametrical slot 3. Consequently when the shank is inserted and the screw 4 drawn up the tapered end 5 of the said screw draws the shank firmly up against the shoulder at the inner end of the slot and at the same time forces the shank firmly against the lateral wall of the socket, thus rigidly holding the attachment to the socket, and consequently to the presser-foot. If desired, both the slot 3 and the attachment end 9 for shank 7 of the presser-foot may be slightly tapered from above downwardly and outwardly, so as to wedge the shank within the socket; but this is not absolutely essential to insure firm retention of the attachment.

In the modification shown in Figs. 5 to 7 the presser-foot C' has its flat shank 7 provided with a contact-surface D, formed by striking up a portion of said shank substantially semicircular in cross-section. Above this contact-surface the tapered depression or opening 8, adapted to be engaged by the

screw 4, is formed. The contact-surface D fits the bore 1 of the socket B, and the tightening effect is the same as in the example previously described when the screw 4 is 5 screwed up. The contact-surface D is located some distance below the top of the shank 7, so as to enable the attachment to be inserted from the side of the socket. The contact-surface may also be slightly tapered 10 outwardly and downwardly toward the sides of the shank.

In Figs. 8, 9, and 10 I have shown a modification in which the contact-surface on the shank 7 of the attachment C² is in the form 15 of two flanges D', adapted to engage with the periphery of the socket when the presser-foot is drawn up by the screw 4. These flanges are preferably tapered downwardly and inwardly, so as to bind on the outside of the 20 socket, and terminate at some distance from the top of the shank, so as to permit lateral insertion into the socket, as before.

It will be readily seen that by providing 25 the several attachments commonly supplied with sewing-machines—such as tuckers, hemmers, &c.—with shanks of the nature described and of standard form all such attachments can be inserted with the greatest 30 ease in a uniform manner after the removal of the presser-foot.

Of course it is to be understood that I do not wish to restrict myself to the application 35 of my invention to sewing-machines and attachments therefor, as it is evident that it can be applied to many other purposes with the same effect.

What I claim as new is—

1. A clamping device comprising a socket provided with a diametrical slot, a screw arranged transversely to the slot and provided 40 with a tapered inner end adapted to cross said slot, and an attachment-piece formed to enter said slot in the socket and provided with a tapered recess adapted to be engaged 45 by the tapered end of the screw; all for the purpose of drawing the attachment-piece upwardly within the slot and forcing the same

against the wall of the socket laterally, substantially as described.

2. A clamping device comprising a socket 50 provided with a diametrical slot and with a longitudinal bore, a screw arranged at right angles to the slot and provided with a tapered inner end adapted to cross said slot, and an attachment-piece provided with a tapered recess 55 adapted to be engaged by the tapered end of the screw and with a curved contact-surface adapted to engage with the wall of the socket; all for the purpose of drawing the attachment-piece upwardly within the slot 60 and forcing the same against the wall of the socket laterally, substantially as described.

3. A clamping device comprising a socket provided with a diametrical slot and with a longitudinal bore, a screw arranged at right 65 angles to the slot and provided with a tapered inner end adapted to cross said slot, and an attachment-piece provided with a tapered recess 70 adapted to be engaged by the tapered end of the screw and with a curved contact-surface diverging from its top and adapted to engage with the wall of the socket; all for the purpose of drawing the attachment-piece upwardly within the slot and forcing the same 75 against the wall of the socket laterally, substantially as described.

4. A clamping device comprising a socket provided with a diametrical slot and with a longitudinal bore, a screw arranged at right angles to the slot and provided with a tapered 80 inner end adapted to cross said slot, and an attachment-piece provided with a tapered recess adapted to be engaged by the tapered end of the screw and with one or more inclined contact-surfaces adapted to engage 85 with the wall of the socket, substantially as and for the purpose set forth.

In testimony whereof I have hereunto set my hand in the presence of two subscribing witnesses.

FREDERICK JACOB, JR.
